UNITED STATES PATENT OFFICE.

WOLFGANG E. SCHWARZMANN, OF LONGMEADOW, MASSACHUSETTS, ASSIGNOR TO
AMERICAN BOSCH MAGNETO CORPORATION, OF SPRINGFIELD, MASSACHUSETTS,
A CORPORATION OF NEW YORK.

ELECTRIC BRUSH.

1,393,704.

Specification of Letters Patent. Patented Oct. 11, 1921.

Application filed February 14, 1921. Serial No. 444,715.

To all whom it may concern:

Be it known that I, WOLFGANG E. SCHWARZMANN, a citizen of the United States, residing at Longmeadow, in the 5 county of Hampden, State of Massachusetts, have invented certain new and useful Improvements in Electric Brushes; and I do hereby declare the following to be a full, clear, and exact description of the invention, such as will enable others skilled in the art to which it appertains to make and use the same.

The present invention relates to ignition systems and has particular reference to contact brush devices such as those that are used in the center post of a distributor or the electrode cap of a collector for a magneto or other parts making use of contact brushes in ignition systems.

- 20 In devices of this type heretofore in use, whether or not the contact brush be employed in a distributor cap, or a distributor rotor, or in connection with a collector on a magneto or otherwise, the brush was usually made of carbon and slidable in a recess of an insert or guide member and was usually connected to an end of a coil spring located within the inner portion of such recess, so that upon the removal of the cap 25 for inspection of the internal parts of the mechanism covered thereby, the brush would be moved outwardly by such spring. The total projection of such brush from its guide member or insert, however, has been prevented by cutting away a side portion of the brush so as to form a shoulder thereon intermediate the ends thereof and by also attaching a hook on the insert with the end 30 of the hook extending in the path of the shoulder so that as the brush was moved outwardly by the spring, the shoulder would contact with the end of the hook, such hook-end thus limiting the outward movement of the brush. In other similar devices, the 35 brush has been provided with a cross pin, the ends of which were capable of having a limited sliding movement in elongated slots formed in the sides of the insert, or by having an elongated slot in the brush 40 with a cross pin extending through such slot and fixed to the sides of the insert. In such structures, however, after the brush and the hook or cross pin were assembled, the brush was permanently held in the recess of the insert and could not be readily 45 removed or replaced in the event of the brush becoming worn, broken or otherwise defective and inoperative. It is, therefore, an object of my invention to construct a contact brush device preventing the total outward movement of the brush but permitting its ready removal and replacement when desired, and to also construct the device so as to avoid the breaking of the carbon brush as well as for making the device 50 strong, durable, efficient in operation and low in cost of construction.
- 55 It is, therefore, a part of the invention to construct a contact brush device with a guide member having a recess in which a brush is slidably located, such brush being preferably carried by a holder which is slid- 60 able in such recess, the holder having a recess in one of its ends and the brush being 65 permanently fastened to such holder in the recess thereof, a resilient means, such as a spring, being located in the recess of the guide member and adapted to move the holder and brush outwardly. Coöoperative with the brush and holder is a detachable means 70 for limiting the outward movement of the holder and brush, such means preferably 75 comprising a shoulder on the holder, intermediate the ends thereof, a groove of preferably annular form being provided in the 80 guide member and a detachable member, the latter being preferably expansible and in the form of a ring and adapted to expand 85 into such groove, so as to coöperate with such shoulder on the holder. The holder 90 preferably has a portion, intermediate its ends, of larger diameter than its end portions, the enlarged portion thus presenting shoulders, one for the engagement with the 95 expansible ring and the other for the engagement of the spring which preferably surrounds one of the end portions of the holder. The other end of the guide member has means for the connection of a lead terminal for the purpose of receiving and 100 conducting electrical current to the brush and holder from such lead.
- 105 In the accompanying drawing illustrating a preferred form of the invention, preferably shown in use with a distributor:
- Figure 1 is a side elevation partly in section of a distributor cap embodying the invention; Fig. 2 is a detail view of a spring used in connection with the contact brush; Fig. 3 is a view in elevation and partly in 110

section of the brush and holder; and Fig. 4 is a top plan view of an expanding ring used for limiting the outward movement of the holder and brush.

Referring more particularly to the drawing, the invention is embodied in a distributor 1 having a distributor cap 2 surmounted by a series of lead posts 3 and a center post 4 to which is connected the lead terminal from the secondary winding of a magneto or induction coil. The distributor cap, comprising the posts 3 and 4, is usually made of suitable insulating material such as bakelite or similar compositions, and in accordance with my invention, I construct the center post of the distributor cap of moldable material and with a metal insert or guide member 5, preferably of cylindrical form, having a knurled surface, and permanently secured or fastened in position within the post 4 at the time of molding the distributor cap, by providing the insert 5 with recesses or an annular groove 6 within which projects an integral molded portion 7 of the post 4 so that the insert 5 will remain in fixed position. Both ends of this insert or guide member are provided with substantially cylindrical recesses 8 and 9, the recess 9, near its opened end being threaded to receive a threaded plug 10, the latter being centrally bored for the passage of the conducting wire or wires 11 of a lead 12 connected to the secondary winding of an induction coil or magneto armature. The end or ends 13 of the conducting portion of the lead 12 projects beyond the member 10 into the bottom of the recess 9 so that when the plug 10 is screwed into place, the lower end 14 of the plug 10 will compress the ends 13 of the conductor into the lower portion of the recess 9, thus making good contact with the metal of the insert or guide member 5 and of the conducting portion of the lead. The post 4 may be surmounted by a cap 15, as in the usual manner, the head of the plug 10 being molded in with the cap 15 as in the case of the insert 5 in the post 4.

In the lower or inner recess 8 of the insert 4 is slidably mounted a metal holder 16 having an intermediate portion of larger diameter than the end portions 17 and 18 thereof, so that the ends of the intermediate portion 16 provides shoulders 19 and 20, respectively, the purpose of which is hereinafter more fully described. The end portion 17 has a recess 21 in which is located a carbon brush or contact piece 22, the latter being preferably tapered or conical at its outer end and projecting outwardly from the recess 21, the outer end portion 23 of the holder end portion 17 being tapered and compressed inwardly or spun over the tapered surface 24 of the carbon contact 22 so as to permanently hold or fasten the contact 22 into place in the recess 21 of the holder. At the inner

portion of the recess 8 is located a coil spring 25 with one end reacting against the shoulder 20 of the holder and the other end against the bottom of the recess 8, the spring 25 continually tending to move the holder, and the parts carried thereby, outwardly, as will be apparent from the view illustrated in Fig. 1 of the drawing. Near the opened end of the recess 8 the insert or guide member has an inner annular groove 26 in which is positioned or expanded an expansible ring 27, this ring being preferably made from a piece of steel wire bent in the form of an annulus and cut or parted along a radius of the annulus so as to permit contraction and expansion thereof, as is clearly shown in Fig. 4 of the drawing.

It will be observed that the ring 27 is so located that as the holder, carrying the brush 22, is moved outwardly by the spring 25, when the distributor cap 2 is removed, the shoulder 19 of the holder will contact with the ring 27 and further outward movement of the holder is thus arrested, thus preventing the projection of the outer end of the brush and the holder to such extent as to render it possible of breaking it by contact with any of the projecting parts of the distributor when the distributor cap is being removed from or inserted into place upon the distributor housing or casing 28. Within the distributor housing 28 is rotatably supported, in the usual manner, a distributor rotor 29 in which is embedded a metal or conducting insert 30 usually disposed radially and coöperative, in a well known manner, with contact pieces located in the posts 3, the latter having leads 31 connected at the other ends thereof to the spark plugs in an internal combustion engine.

In use, when the distributor cap 2 is removed, the spring 25 will move the holder, and the brush 22 carried thereby, outwardly until the shoulder 19 contacts with the ring 27, further movement being thus prevented. It will thus be observed that the brush will not project a great distance from the cap 2. Upon replacing the cap upon the housing 28, should the brush 22 contact with any projecting element within the distributor housing, it will not be broken or thrown out of the socket or recess found within the insert 5, and, accordingly, the brush will not be made inoperative, as in the old type of devices. As the cap is moved into proper position the brush 22 will contact with the conducting plate or insert 30, the spring 25 compressed and the holder and the brush caused to move inwardly along the recess 28, into the operative position of the device, as is shown in Fig. 1 of the drawing.

If it be desired to remove the holder and brush entirely from the insert 5, the ring 27 may be contracted or compressed so that it may be readily removed from the groove

26, and the holder, with the brush and the spring 25, may be bodily removed.

It will also be apparent that in assembling the parts the spring is first inserted in 5 the recess 8 and the holder next inserted, and then the ring 27, which while in contracted form, is placed into the opening of the recess 8 and permitted to expand into the groove 26. It will be thus noted from 10 the above that the assembling and the replacing of the parts are readily and conveniently made.

Having thus described my invention what I claim is:

15 1. A contact brush device comprising a guide member having a recess, a brush slideable in said recess, resilient means for progressively moving said brush outwardly when it wears, and a detachable means constructed and arranged to permit progressive movement of said brush and coöperative with said brush to limit the maximum outward movement thereof, whereby upon removing said detachable means, said brush 25 may be removed from said recess.

2. A contact brush device comprising a guide member having a recess, a brush holder slideable in said recess, a brush carried by said holder, resilient means for moving said 30 holder outwardly, and a detachable means coöperative with said holder to limit the outward movement thereof, whereby upon removing said detachable means, said holder and brush may be removed from said recess 35 of said member.

3. A contact brush device comprising a guide member having a recess, a brush holder having a recess in an end thereof and slideable in said recess of said guide member, a 40 brush permanently fastened to said holder in said recess thereof, resilient means for moving said holder outwardly, and detachable means coöperative with said holder to limit the outward movement thereof, whereby 45 upon removing said detachable means, said holder and brush may be removed from said recess of said member.

4. An ignition contact brush device comprising a guide member having a recess, a 50 brush holder having a recess in an end thereof and having a shoulder intermediate the ends thereof, said holder being slideable in said recess of said member, a brush permanently fastened to said holder in said recess 55 thereof, resilient means for moving said holder outwardly, and detachable means coöperative with said shoulder on said holder to limit the outward movement thereof, whereby upon removing said detachable 60 means said holder and brush may be removed from said recess of said member.

5. A contact brush device comprising a guide member having a recess, a brush slideable in said recess, resilient means for pro- 65 gressively moving said brush outwardly

when it wears, a detachable member constructed and arranged in said recess to permit progressive movement of said brush, and coöperative with said brush to limit the maximum outward movement thereof, 70 whereby upon removing said detachable member, said brush may be removed from said recess.

6. An ignition contact brush device comprising a guide member having a recess, a 75 brush slideable in said recess, resilient means for moving said brush outwardly, an expansible detachable member in said recess and coöperative with said brush to limit the outward movement thereof, whereby upon 80 contracting and removing said detachable member, said brush may be removed from said recess.

7. A contact brush device, comprising a guide member having a recess provided with 85 an annular groove, a brush slideable in said recess, resilient means for moving said brush outwardly, an expansible detachable member in said groove and coöperative with said brush to limit the outward movement thereof, whereby upon contracting and removing said detachable member, said brush may be removed from said recess. 90

8. An ignition contact brush device comprising a guide member having a recess provided with an annular groove, a brush slideable in said recess, resilient means for moving said brush outwardly, an expansible detachable ring expanded into said groove and coöperative with said brush to limit the outward movement thereof, whereby upon contracting and removing said ring, said brush may be removed from said recess. 100

9. A contact brush device comprising a guide member having a recess in an end 105 thereof and having means at the other end thereof for the connection of a lead terminal, a brush holder having an intermediate portion of larger diameter than the end portions thereof for providing shoulders 110 at each end of said intermediate portion, said intermediate portion being slideable in said recess of said guide member, one of said end portions having a recess, a carbon brush fastened in said recess of said holder, a 115 spring bearing against one of said shoulders in said recess of said guide member and surrounding an end portion of said holder for moving said holder outwardly, said guide member having an annular groove 120 near the open end of the recess thereof, a detachable expansible ring in said groove coöperative with another of said shoulders to limit the outward movement of said holder, whereby upon contracting and removing said ring, said brush may be removed from said recess. 125

In testimony whereof I affix my signature.

WOLFGANG E. SCHWARZMANN.
